GEAR TRAIN FOR KINETOGRAPHIC PROJECTORS AND SIMILAR MECHANISMS

George A. Mitchell, Pasadena, and Emanuel C. Manderfeld, Los Angeles, Calif., assignors to Mitchell Camera Corporation, Glendale, Calif., a corporation of Delaware

Application October 14, 1947, Serial No. 779,702

2 Claims. (Cl. 88—18.3)

1

This invention is concerned generally with machines for handling flexible film strips, and relates more particularly to a mechanism for driving the various moving parts of motion picture projection machines and the like.

Film is ordinarily fed through such machines by engagement first with a continuously moving "pull down" sprocket which draws film at a predetermined rate from a supply reel; then with an intermittent mechanism, which may be of claw type but more typically comprises an "intermittent" sprocket and a mechanism such as a Geneva for intermittently rotating it; and finally with a continuously moving "hold back" sprocket (sometimes physically the same as the pull down sprocket) which feeds the film at a predetermined rate to a takeup reel, or to other apparatus such as a sound head. The rates of film feed over the two continuously moving sprockets must be equal, and must equal the average rate of film feed over the intermittent sprocket. These conditions are ordinarily satisfied by driving the two continuously moving sprockets and the intermittent mechanism, which in turn drives the intermittent sprocket, from a single power source through a suitable gear train.

An important object of the present invention is to provide an improved gear train for the purpose just outlined. Among the principal characteristics of a preferred form of film feeding gear train in accordance with the invention is the fact that the sprocket driving gears, directly mounted respectively on the shafts of the continuously moving sprockets, and also the driven gear on the intermittent driving shaft, are all directly engaged by a single intermediate gear. Such an arrangement has a number of important advantages, among which are: the relatively small number of working gears, making for smoothness and accuracy of operation and for economy of construction and maintenance; the fact that all working gears, or more accurately all meshing pairs of working gears, can be, and preferably are, provided with hunting teeth, giving longer life and better interchangeability of parts; and the fact that all working gears of the film feeding gear train operate in the same plane, permitting straightforward, economical mounting of the gears and the use of simple gear types.

In preferred form the invention includes a manual framing adjustment of the intermittent mechanism, by which the longitudinal position of the film, as it is intermittently drawn past the film gate, can be so adjusted that successive picture frames of the film are momentarily

2

brought to rest in proper registration with the film aperture. The intermittent mechanism is of the Geneva type, with the intermittent sprocket mounted directly on the star cam shaft of the Geneva. The pin cam is mounted on a pin cam shaft which is parallel and eccentric to the star cam shaft and is driven from the intermittent drive shaft, mentioned above, which is parallel to and coaxial with the star cam shaft. The pin and star shafts, and preferably also the intermittent drive shaft (but the latter is not necessary) are mounted in a unitary intermittent housing which is adjustably mounted on the main frame of the machine for rotation about the common axis of the star cam and drive shafts. The framing adjustment is accomplished by turning the intermittent movement bodily about this axis, thus rotating the intermittent sprocket and modifying the framing as may be required.

20 An object of the present invention is to provide an improved intermittent gear train for driving the pin cam shaft of the Geneva from the intermittent drive shaft; and, more particularly, to relate the intermittent gear train to the film feeding gear train in such a way that all pairs of engaged gears can embody the principle of hunting teeth, while still maintaining a simple overall speed ratio between the driven pin cam shaft and the continuously moving sprockets mentioned above.

25 The optical projection system by which successive film frames, momentarily positioned at the film aperture, are projected onto the screen generally includes a light source, condensing system and projection lens, lying on a well-defined optical axis which is substantially normal to the plane of the film aperture. The axes of the three film engaging sprockets mentioned above are preferably parallel to the plane of the film aperture, and hence normal to the optical axis. During the periods of film motion past the film aperture the projection light is cut off by one or more shutters, which are ordinarily and preferably rotating disk shutters mounted on a shutter shaft 30 which is parallel to the optical axis, and hence normal to the axes of the sprockets. However, it lies within the purview of our invention that barrel type shutters may be used, in which event the shutter shaft will lie on an axis parallel to the axes of the sprockets.

35 The present invention includes, in addition to the film feeding gear train and intermittent gear train, already mentioned, means for driving the shutter shaft in adjustable synchronism with the sprockets. The shutter driving gear train of the

invention includes a single intermediate shaft, here referred to as the jack shaft, which is directly geared both to the shutter shaft, on the one hand, and to one of the shafts of the film feeding gear train, on the other, and thus forms a driving connection between them. One of the gear connections of the jack shaft (either to the shutter shaft or to the film driving train) is in the form of a pair of intermeshing helical gears which are relatively axially shiftable to adjustably change their relative phases of rotation. Such a phase-shiftable set of intermeshed helical gears may be used between shafts that are mutually parallel or that lie at an angle to each other.

Hence, if the shutter is of the type having its axis parallel to the sprocket shafts, the mutually shiftable gears can be used on parallel shafts either to drive the jack shaft or to drive the shutter shaft from the jack shaft. On the other hand, if the shutter shaft, as is at present preferred, lies at right angles to the sprocket axes, the jack shaft can lie parallel either to the shutter shaft or to the sprocket axes; and the relatively shiftable helical gears can then be used to interconnect either a pair of parallel, or a pair of crossing, shafts.

In the present preferred form, the jack shaft is parallel to the preferred shutter shaft and therefore at right angles to the sprocket axes; and in that arrangement the axially shiftable helical gears are applied between the parallel shutter and jack shafts, and the latter is driven from a convenient shaft or gear associated with the sprocket driving train. Axial motion of one helical gear relative to the other results in relative rotation of the two gears and has the effect of altering the relative timing of the shutter shaft and shutter with respect to other parts of the drive, particularly the intermittent mechanism.

The driving connection mentioned above between the jack shaft and a non-parallel shaft is the only instance in the entire gear system of the preferred form of the invention in which mutually engaged working gears have non-parallel axes. This permits the general use of gears of simple types, which are readily mounted and give relatively smooth operation and long service.

Since manipulation of the manual framing adjustment, by which the intermittent housing is turned bodily about the axis of the intermittent sprocket, alters the timing or phase relation between the intermittent mechanism and other parts of the machine, including the shutter shaft, a timing compensating mechanism is provided in the shutter driving gear train, by which the relative phase relation between shutter and intermittent is made independent of the framing adjustment of the intermittent. The timing compensation mechanism preferably makes use of the pair of helical gears by which the jack shaft of the shutter drive is related either to the shaft of the film feed gear train which drives it, or to the shutter shaft itself. One of those gears is axially movable on its shaft, as has been described, and its axial motion is under the control, by means of a suitable linkage, of the rotational adjustment of the intermittent mechanism housing. The linkage just referred to is such as to automatically produce the correct variation in the shutter timing to just compensate for the change in timing of the intermittent mechanism resulting from any framing adjustment of the latter. The shutter timing compensation mechanism includes also a trimming adjustment for the shutter timing, as will be described.

As in the film feeding gear train and inter-

mittent gear train, all the working gears of the shutter drive can be, according to the present invention, and preferably are, arranged with hunting teeth. The gear systems and the shutter synchronizing system are such that this advantage is attained without adding any complications to the gear systems. In fact the present invention has the great advantage of requiring only ten working gears in the entire film and shutter mechanism, including the three groupings described above as the film feeding gear train (four gears), the shutter drive gear train (four gears), and the intermittent gear train (two gears). Those ten working gears include six pairs of meshing gears. Only one of the six pairs involves gears not operating in one plane; and all pairs of meshing gears can have hunting teeth. These and other characteristics of the invention permit simplification of the mechanical design as compared with previous projection machines and lead to superior operation and longer life of the parts.

A clear understanding of the invention, and of further characteristics and advantages of it, will be obtained from the following illustrative example of its embodiment in a typical motion picture projection machine. This description, which is not intended to limit the scope of the invention, is to be read in conjunction with the accompanying drawings, of which:

Fig. 1 is a side elevation, partly cut away, showing a projection machine in accordance with the invention, with the door to the film compartment open, the aspect of this view being indicated by line 1—1 of Fig. 3;

Fig. 2 is a vertical longitudinal section through the gear compartment of the machine, taken as indicated by line 2—2 of Fig. 3;

Fig. 3 is a vertical transverse section taken generally as indicated by lines 3—3 of Fig. 1 and Fig. 2;

Fig. 4 is an enlarged vertical section along the axis of the intermittent movement, taken as indicated by line 4—4 of Fig. 2;

Fig. 5 is a transverse section through the intermittent movement, taken as indicated by line 5—5 of Fig. 4;

Fig. 6 is a section similar to Fig. 5, but taken on line 6—6 of Fig. 4.

Numeral 10 in the drawings indicates a frame or casing on and in which the various parts and subassemblies of the machine are mounted, and which serves also as a housing, enclosing the working parts of the machine. Frame 10 includes side walls and a central vertical partition 15 which divides the interior of the frame into a film compartment 16 (Fig. 1) and a gear compartment 17 (Fig. 2). Access to film compartment 16 is through a door hinged to frame 10 at 21 and indicated in open position at 20. Access to gear compartment 17 is obtained by removing cover plate 23.

The motion picture film to be projected, indicated generally at 25, is carried on a reel in magazine 30, from which it is drawn through an opening in frame 10, indicated schematically at 31, by pull-down sprocket 32. A sprocket clamp, indicated generally at 33, maintains the perforated film in engagement with the sprocket teeth in the usual way. The film passes next via a loose film loop 35 to the film chute 36 which lies between the fixed film trap 38 and the film gate 40.

Gate 40 is movably mounted on rails 41 to facilitate threading of the film, and can be moved

away from trap 38 by merely moving the handle 43 of gate control lever 42 to the right in Fig. 1. This motion first rotates lever 42 counterclockwise around its pivoted connection 44 to the gate, lifting lever pin 45 out of side leg 47 of L-shaped slot 46 and unlatching the gate, and then moves the gate to the right on rails 41. After threading, the gate is relatched by merely moving handle 43 to the left in Fig. 1, first sliding the gate on rails 41 into closed position and then rotating lever 42 clockwise so that pin 45 enters latch slot 47.

Film trap 38 carries a removable aperture plate 48 in which is located the film aperture 49 (see Fig. 3) of the projection system. The film is intermittently drawn past aperture 49 by intermittent sprocket 50, successive picture frames of the film being momentarily brought to rest in register with the aperture. Intermittent sprocket clamp 51 is shown supported on the lower end of movable film gate 40. The film next passes via loose film loop 52 to hold back sprocket 54, provided with the usual sprocket clamp 55, from which it is drawn by means not shown through an opening 56 in casing 10 to a takeup reel or to other apparatus such as a conventional sound head.

The projection system includes a light source such as an arc lamp and condensing system mounted in a lamp house indicated schematically in Fig. 1 at 60 and delivering a beam of concentrated light along the optical axis 61 of the projector. The light beam passes into the rear shutter housing 63, where it is intermittently intercepted by rotating rear shutter 65, mounted on shutter shaft 66 (see below). When not intercepted by the shutter, the light passes through several suitable openings in case 10, in sight box 69 and (under operating conditions) in dowser and fire shutter assembly 70, and then through aperture 49 in plate 48 to illuminate the area of film which is framed by film aperture 49. The various parts and apertures mentioned in the immediately preceding sentence are not shown or described in detail, as not related directly to the present invention. Light transmitted by the film traverses an opening schematically indicated at 40a in film gate 40 and passes through projection lens 72, which forms an image of the film on the screen (not shown). An aperture, indicated at 73, in the front wall of case 10 transmits the light beam from the lens. A front shutter 75, mounted on shutter shaft 66 in front shutter housing 76, cooperates with rear shutter 65 in the usual manner. Projection lens 72 is suspended from ways parallel to optical axis 61 and is adjustable for focus under control of handle 71. The details are not necessary to the present invention.

Rear and front shutters 65 and 75 are separately adjustable on shutter shaft 66 by any suitable means, such, for example as rear and front shutter hubs 67 and 77 which are releasably clamped to shutter shaft 66. The shutters are so set on the shaft as to give the most advantageous timing relation both between the cooperating but distinct action of the separate shutters upon the light beam, and between the combined action of the shutters collectively and that of the intermittent film moving mechanism. For clarity in the present description it will be assumed that the two shutters are properly adjusted on their common shaft with respect to each other, and that the shaft—or the shutters together on the shaft—are in approximately the correct rotational phase relation to the intermittent mech-

anism. Improved means for achieving final adjustment of the latter relation, here referred to as the shutter timing, and for maintaining that relation under operating conditions, form a part of the present invention, and are described below.

In the form illustrated the intermittent mechanism is mounted as a unit within a housing 80 (see Figs. 4, 5, and 6) which includes a generally cylindrical case 81 and a cover plate 82 which is secured to one face 83 of case 81 as by screws 84 and a single locating pin 85. (See Fig. 1.)

Outer cylindrical surface 88 of case 81 is journaled in circular opening 89 in frame partition 15, and is located axially by flange 90 of cover plate 82, which fits under cooperating flange 91 of retaining ring 92. Intermittent housing 80 is thus rotatable in the frame partition 15, and is removable as a unit in an axial direction to the right in Fig. 4 after removal of retaining ring 92.

Intermittent sprocket 50 is rigidly mounted on star cam shaft 95, which carries also star cam 96 of an intermittent mechanism of the Geneva type, and which is journaled in an axial bore 97 in cover plate 82 on an axis coincident with the axis of rotation of case 81. The pin cam 98 of the Geneva mechanism is rigidly mounted on pin cam shaft 99, which is journaled in bushing 100. Shaft 99 is adjustable in position to adjust the engagement of gears 105, 106; and cover 82 is also adjustable to adjust the engagement of the Geneva pin with the star, but those features do not enter into the present invention.

Pin cam shaft 99 carries also gear 105 which is engaged and driven by pin cam driving gear 106, mounted rigidly on the inner end of intermittent drive shaft 108. The latter shaft is journaled (preferably in case 81) coaxially with star cam shaft 95, and hence coaxially with both intermittent sprocket 50 and journal 89 of intermittent housing 80. The axial position of shaft 108 is defined by gear 106 at the inner end and lock nuts 109, threaded to the shaft at 107 at the outer end of its journal 104. The outer end of shaft 108 projects from housing 80 (to the left in Fig. 4) and carries intermittent driving gear 110 and flywheel 111, which are preferably either formed integrally or securely connected together to form a unit, as by force-fitting the flywheel over gear hub 110a. This unit is removably keyed or splined to shaft 108, as indicated at 112, and is axially secured to the shaft by a retaining member 115. This retaining member, in the form illustrated, is threaded at 117 to the end of shaft 108 in the manner of an ordinary retaining nut, and engages axially transverse surface 116 of gear 110, releasably locking the gear and flywheel 111 to the shaft. Further details of the structure and functions of member 115 and associated parts are described in copending patent application, Ser. No. 779,789, filed Oct. 14, 1947, by applicant Emanuel C. Manderfeld.

The purpose of the above described arrangement, insofar as the present invention is concerned, is to allow of rotative adjustment of the intermittent sprocket and the Geneva movement 65 about the axis of the sprocket. To provide for that, it is only necessary that a frame or case (e. g. the case 81) carry the pin shaft and its gear and cam in such manner that they can be rotated about the axis of the sprocket and the axis of gear 106. Gear 106, or its shaft 108, can therefore be journaled either in the main frame of the mechanism or in the intermittent housing 80; and it can be driven from the general gear train in any suitable manner. It is, however,

preferably mounted and driven as shown to facilitate removal and replacement of the intermittent mechanism. Features of the mechanism relating directly to removal and replacement of the intermittent movement are the subject matter of the said copending application, and are not claimed in the present application.

The rotational position of intermittent housing 80 in its journal 89 is determined by manual adjustment of framing knob 120 or 121 (see Fig. 3). These are rigidly mounted on opposite ends of framing shaft 122, which is journaled as shown in Fig. 3 at 123 and 124 in the outer wall and in partition 15 of case 10. Framing shaft 122 is linked by framing gear 125 and idler 126 to gear sector 127, cut in a portion of the periphery of case 81, as shown particularly in Fig. 5. Rotational adjustment of knob 120 or 121 is transmitted by gears 125, 126 and sector 127 to the entire intermittent unit 80. This has the effect of adjustably rotating intermittent sprocket 50, and changes the longitudinal position in which the film is momentarily stopped in front of film aperture 49, and is used to correct the framing of the film when necessary.

Rotational adjustment of intermittent housing 80, in addition to the framing action just described, carries pin cam shaft 93 and pin cam driven gear 105 bodily around shaft 108, which carries pin cam driving gear 106. This causes gear 105 to roll on gear 106, rotating pin cam 93 with reference to housing 80, and hence also with reference to start cam 96 of the intermittent mechanism. This alters the phase relation of the intermittent with respect to intermittent driving gear 110. For example, if housing 80 is rotated clockwise in Figs 1 and 6 to move the film downward at aperture 49, pin cam 93 turns clockwise through a corresponding angle with respect to casing 81. This is opposite to its normal operating rotation, and therefore retards the beginning of the next engagement with start cam 96. In other words the phase of the intermittent action has been delayed with respect, for example, to the rotation of intermittent driving gear 110. The shutter action, normally linked in a definite timed relation to gear 110, must be similarly delayed with respect to that gear, if the proper phase relation between the intermittent and the shutter is to be maintained. Such compensation of the shutter timing is obtained through the shutter drive gear train, under direct control of the rotational framing motion of intermittent housing 80.

A spur gear sector 130 on case 81 engages circular rack teeth 131 on cylindric rack bar 132. The rack teeth 131 on bar 132 are of spur form but extend circularly around the cylindric bar so that the bar may be rotated without affecting its longitudinal position with relation to gear sector 130. Rotational motion of housing 80 produces a corresponding longitudinal motion of rack bar 132, which is slidably and rotatably journaled at 133 and 134. One of a pair of helical gears at some point in the gear train which drives shutter shaft 66 in timed relation to intermittent driving gear 110 is slidably splined to its shaft. The sliding motion of rack bar 132 is transmitted to that gear, which is gear 141 in the present instance, and moves that gear axially with respect to the other helical gear (140) of the pair. That relative axial motion of the helical gears results in a corresponding relative rotational motion, and therefore rotates shutter shaft 66 with respect to those parts to which it

is linked by the helical gears. Since the latter parts include intermittent driving gear 110, the result is seen to be a shutter phase shift of the required type. A shift in the proper direction and of the proper size to give accurate compensation can be obtained by correct choice of such factors as the hand and angle of the threads of the helical gears, the diameter of the fixed helical gear, and the radius of sector 130.

In the present embodiment, the helical gears by which the shutter is rotationally adjusted constitute the connection between the shutter shaft and parallel jack shaft 142. This location of the helical gears has the advantage that the longitudinal motion of rack bar 132 is parallel to the required direction of motion of the splined helical gear, and can be transmitted to it directly without unnecessary linkages. Although either one (or both) of the helical gears may be axially movable, the preferred arrangement is that illustrated in which helical gear 140 is rigidly mounted on shutter shaft 66 and in engagement with helical gear 141, which is rotationally fixed but longitudinally movable on jack shaft 142, being splined to the shaft at 145. Axially movable gear 141 is embraced by yoke 135, which is longitudinally adjustably fixed on rack bar 132 by axial threads 137, and which transmits the sliding motion of the rack bar directly to the gear. With this arrangement, the shutter is driven by a gear train which acts through jack shaft 142 and includes the pair of helical gears 140, 141. Shutter shaft 66 extends forward through front shutter housing 76, and carries hand wheel 147, by which the entire gear mechanism can conveniently be turned over by hand.

Generally speaking, if we assume the ratio of the internal intermittent gears (105, 106 in the present instance) to be unity, then the angle of retard of the film movement is equal to the angle through which intermittent casing 81 has been rotated. The corresponding amount of longitudinal shifting of rack bar 132 depends on the pitch diameter or gear sector 130. If the helical angle of the teeth of gears 140 and 141 is 45°, say, then the peripheral shifting of gear 140 and shutter shaft 141 will be equal to the longitudinal shift of bar 132. If then the pitch diameter of gear sector 130 is made equal to that of gear 140, the shutter shaft will be moved through an angle equal to the angle of rotation of intermittent case 81.

However, as pointed out later in connection with provision of hunting teeth in the gear trains, the ratio at gears 105, 106 is not unity, gear 106 having twenty five teeth and gear 105, twenty two teeth. In that arrangement, the relative retard of the intermittent movement is 25/22 of the angle of framing adjustment of intermittent case 81. That, or any other specific ratio, can be taken care of by correspondingly changing either the pitch diameter of sector 130, or that of gear 140, or by making the helical angle of the teeth in gears 140, 141 to suit. This last method is preferred because the choice of any helical angle does not involve the gear ratio at 140, 141 and leaves that ratio to be set solely by other considerations (see below); and also because it is not necessary to adopt any particular ratio between the pitch diameters of gear 140 and sector 130. For instance in the illustration given, if those two pitch diameters are equal, then the helical angle of gears 140, 141, measured with reference to the axis, is one whose tangent is 25/22. If the pitch diameters of gears 130 and

140 are not equal, then the adopted pitch angle is one whose tangent is 25/22 multiplied by the ratio of pitch diameter of gear **140** to that of gear sector **130**.

Fine adjustment of shutter position (phase) with relation to the phase position of the intermittent movement, during operation, is provided for by rotating the rack bar **132** to screw-threadedly adjust the longitudinal position of yoke **135** and helical gear **141** with relation to the bar. That rotation does not disturb the longitudinal position of the bar with relation to gear sector **130** nor with relation to the phase position of the intermittent movement. It therefore changes the phase relation of the shutter by sliding gear **141** longitudinally and thereby rotating gear **140** a corresponding amount. The bar may be rotatively adjusted by any means which does not interfere with its longitudinal framing movement, and which is not affected in its operation by the longitudinal framing movement. For instance, the end of bar **132**, or a cylindric member mounted on it, is provided with straight axial teeth—in effect, long spur gear teeth—as shown at **132a**. A rotatable rod **132b**, lying at substantially right angles to rod **132**, has a screw thread of small pitch, **132c**, meshing in the spur gear teeth. The rod projects through partition **15**, and at its end which is available in film compartment **16** (see Fig. 1) it has a formation **132d** to receive a screw driver or other suitable tool to rotate it.

The principal driving connections of the projector have the main function of driving four cooperating parts in accurate, and, in certain respects, adjustable timed relationship with each other. Those parts are the two continuously driven film feeding sprockets **32** and **54**, shutter shaft **66** and pin cam shaft **99** of the Geneva movement which drives intermittent sprocket **50**.

One complete rotation of pin cam **98** results in one quarter rotation of intermittent sprocket **50**, the sprocket being of such size that one quarter rotation moves the film one frame spacing. Therefore to obtain an average rate of intermittent sprocket rotation equal, say, to the rate of rotation of pull down sprocket **32** (assuming, for example, equal numbers of teeth on the two sprockets) the pin cam **98** of the intermittent mechanism must be driven four times as fast as sprocket **32**. This means that the overall gear train connecting sprocket **32** and pin cam shaft **99** must have the simple integral gear ratio of four to one. (If sprockets **32** and **50** have unequal numbers of teeth, the value of the overall gear ratio will vary correspondingly.) The gear ratio of the intermittent gear train itself, comprising gears **105** and **106**, is arbitrary, so long as it is properly related to the remainder of the overall drive. Incorporation of a hunting tooth in the action of gears **105** and **106** requires that the respective numbers of teeth of the two gears, and hence also their respective rates of rotation, be incommensurable. This is permissible only if the remainder of the overall gear system is such that intermittent drive shaft **108** can be driven at a rate incommensurable with that of pull-down sprocket **32**, and so related to it as to give the required overall integral speed ratio of (in the present instance) four to one. The same requirement applies to the gear train between intermittent drive shaft **108** and holdback sprocket **54**. As will be seen, the gear system of the present invention, in addition to being remarkably simple, satisfies the conditions just described.

Pulldown sprocket **32** is rigidly mounted on sprocket shaft **160**, which is journaled in boss **161** on partition **15** of the machine frame. Sprocket shaft **160** protrudes into gear compartment **17** and carries sprocket driving gear **162** rigidly mounted on the protruding shaft end.

Holdback sprocket **54** is similarly mounted on sprocket shaft **170**, which is journaled in partition **15** and also in the outer wall of gear compartment **17**, and projects through that wall to the exterior of frame case **10**, as indicated in Fig. 2, to serve as the initial driving shaft of the mechanism. Sprocket driving gear **172** is rigidly mounted on shaft **170** in gear compartment **17**. The two sprocket gears **162** and **172** are preferably in a common plane which also passes through driven gear **110** on intermittent drive shaft **108**. The three gears **162**, **172** and **110**, are connected together by the single intermediate gear **175**, which is in direct mesh with all of them. Intermediate gear **175** is shown as an idler gear lying in the common plane of gears **162**, **172**, and **110**, and rotatably mounted on stud shaft **176** which is mounted at **177** on partition **15** of the frame.

The correct relative speed ratio of the two uniformly moving sprockets **32** and **54** is obtained, according to the invention, by providing the corresponding sprocket driving gears **162** and **172** with respective numbers of teeth in direct proportion to the numbers of peripheral sprocket teeth **34** on the respective sprockets. If, as in the illustrative preferred embodiment, the sprockets have equal numbers of teeth, gears **162** and **172** also have equal numbers of teeth, and are thus constrained by intermediate gear **175** to rotate at equal speeds. The ratio of the speeds of sprockets **32** and **54** is entirely independent of the number of gear teeth on intermediate gear **175**, and that gear can therefore be made incommensurable in numbers of teeth with both sprocket driving gears. For example, in the present preferred embodiment in which sprockets **32** and **54** have equal numbers of sprocket teeth, gears **162** and **172** each have 88 teeth and intermediate gear **175** has 89 teeth, a number which is incommensurable with 88. Hence the hunting tooth principle applies between intermediate gear **175** and both sprocket gears, and yet the sprockets turn at the same speed.

The speed of pin cam shaft **99**, relative, say, to that of pulldown sprocket **32**, is also independent of the number of teeth on intermediate gear **175**. It is completely determined by two ratios, first, the ratio of the number of teeth on sprocket driving gear **162** to that on pin cam driven gear **105**; and second, the ratio between the numbers of teeth on the two gears **106** and **110** on intermediate drive shaft **108**. Neither one of those ratios involves gears which are directly engaged with each other. This makes it possible to choose the actual numbers of teeth of the various gears in such a way as to maintain simple integral values for the two ratios just defined (leading to the required overall gear ratio of four to one) and yet to make all pairs of interengaged gears mutually incommensurable as to numbers of teeth.

In particular instance, if the two gears **106** and **110** on intermittent drive shaft **108** have equal numbers of teeth, (the actual number being arbitrary) the second ratio defined above is unity, and the first ratio gives directly the overall gear ratio, which in the present instance must be four to one. Then, with 88 teeth on each of the

sprocket driving gears, pin cam driven gear 105 must have 22 teeth. The actual number of teeth on the two intermittent drive shaft gears, 106 and 110, can then be so chosen as to be incommensurable both with the number of teeth on pin cam driven gear 105 and with the number of teeth on intermediate gear 175. In the present embodiment, for example, gears 106 and 110 have 25 teeth each, a number which is incommensurable with the 22 teeth of gear 105 and also with the 89 teeth of gear 175. In this way the hunting tooth principle is applied with respect to all pairs of engaged working gears throughout the film feeding and intermittent gear trains.

The shutter gear train, according to the present invention, includes only one pair of gears in addition to helical gears 140 and 141, already described. When, as in the present instance, jack shaft 142 is parallel to shutter shaft 66, it is directly driven by a pair of engaged gears of any suitable type from a shaft at right angles to it. That shaft may be either one of sprocket shafts 160 and 170, intermittent drive shaft 108 or, as in the modification here illustrated, the short hub sleeve which carries intermediate gear 175. As shown, a large bevel gear 180 is formed integrally with intermediate gear 175, and drivingly engages a smaller bevel gear 181 rigidly mounted on jack shaft 142. This arrangement gives a shutter drive from bevel gear 180 which is in many respects analogous to the intermittent drive already described from intermediate gear 175 to pin cam shaft 99 of the intermittent movement. In particular, the two drives are similarly well adapted for yielding a simple integral overall gear ratio for the ultimate driven element with respect, say, to pulldown sprocket gear 162, and at the same time for introduction throughout the train of a hunting tooth in every pair of engaged gears. These objectives are attained, for example, in the particular system illustrated, by employing 89 teeth on bevel gear 180, 23 teeth on bevel gear 181 which it drives, 23 teeth also on jack shaft helical gear 141, and 22 teeth on helical gear 140 on shutter shaft 66. Thus, all engaged gear pairs have incommensurable numbers of teeth. The gear ratio between sprocket shaft 160 and shutter shaft 66 is determined by the tooth ratio of gears 162 and 140 and the tooth ratio of gears 141 and 181 on jack shaft 142. The latter ratio is commensurate; specifically it is unity in the illustration given, but need not be so. Thus, in the specific illustration, the overall ratio between the sprocket shaft and the shutter shaft is one to four, the same as between the sprocket shaft and the pin cam shaft 99 of the intermittent movement, and the shutter shaft makes one revolution for each film-moving operation of the intermittent mechanism. Throughout this description shutters making one revolution per cycle of film movement (having, in effect, one film exposing opening) have been assumed. If shutters making less than one revolution per cycle should be used the overall gear ratio between the intermittent movement shaft 99 and the shutter shaft 66 will be changed accordingly, but the principles and advantages of the invention apply equally well.

The overall result of the present improved driving connections is to give positive speed relations between two continuously moving sprockets, the intermediate sprocket, and the shutter, using for that purpose a remarkably small number of working gears, most of which

are of a comparatively simple type and are subject to relatively little wear. The life and smoothness of operation of the machine, as well as the interchangeability of parts, are improved by the fact that the gear system is well adapted for the use of hunting teeth in connection with all engaged working gears. And the system, with those advantages, also admits of and includes the simple type of framing compensation, between the intermittent movement and shutter, that has been described.

We claim:

1. In a motion picture projection machine which includes a continuously rotatable film feeding sprocket, an intermittent mechanism of the Geneva type driving an intermittently movable sprocket and having a driving shaft on an axis parallel to the axis of the continuously rotatable sprocket and co-axial with the axis of the intermittent sprocket, a housing for the intermittent mechanism mounted to be rotatively adjustable bodily about the axis of the intermittent sprocket, and a shutter and a shutter shaft located on an axis which lies substantially at right angles to the axes of the two sprockets; driving and control interconnections between the continuously movable sprocket, the intermittent mechanism and the shutter shaft, said interconnections comprising a driving gear in direct driving relation to the continuously moving sprocket, a driving gear for the intermittent mechanism mounted directly on the intermittent mechanism driving shaft, an intermediate gear in direct mesh with each of the two first mentioned gears, said three gears all lying in a single plane, a jack shaft on an axis parallel to the shutter shaft, intermeshing gears driving the jack shaft from the intermediate gear, a pair of intermeshing helical gears on the shutter shaft and jack shaft, both said gears being rotatively fixed to their shafts and one of said gears being axially movable, a gear sector on the intermittent housing in the plane of its rotative adjustment, a cylindric rack bar mounted for axial movement along and rotation about an axis parallel to the jack shaft, circular rack teeth on the bar meshing with said gear sector, screw threads on the rack bar, a yoke mounted on the rack bar and engaging said threads so as to be adjustably positioned on the bar by rotation of the bar, the yoke engaging the axially movable helical gear to impart axial adjustment movement to it, and means for rotatively adjusting the rack bar.

2. In a motion picture projection machine which includes a continuously rotatable film feeding sprocket and an intermittently movable sprocket mounted respectively on parallel shafts, an intermittent housing mounted to be rotatively adjustable about the axis of the intermittent sprocket, an intermittent mechanism of the Geneva type carried by the housing and including a pin cam shaft parallel to and eccentric of the said axis and in driving relation to the intermittent sprocket, and a shutter and a shutter shaft located on an axis substantially at right angles to the sprocket axes; driving and control interconnections between the continuous sprocket, the intermittent mechanism and the shutter shaft, said interconnections comprising a sprocket driving gear fixed on the shaft of the continuous sprocket, an intermittent mechanism driving shaft coaxial with the intermittent mechanism sprocket, an intermittent mechanism driving gear mounted on the intermittent mechanism driving shaft, a pair of intermeshing

gears fixed respectively on the pin cam shaft and on the intermittent mechanism driving shaft, a jack shaft parallel to the shutter shaft, a jack shaft driving gear rotatively fixed to the jack shaft, a pair of intermeshing helical gears mounted respectively on the shutter shaft and on the jack shaft, both said gears being rotatively fixed to their shafts and one of said gears being axially movable, means acting by virtue of rotational adjustment of the intermittent housing to axially shift the axially movable helical gear, and two intermediate gears rotatively fixed together and in direct mesh respectively with the jack shaft driving gear and with both the sprocket driving gear and the intermittent mechanism driving gear; the sprocket driving gear, the gear on the pin cam shaft and the gear on the shutter shaft having respective numbers of teeth that are mutually commensurable, the two intermediate gears having respective numbers of teeth that are mutually commensurable and are incommensurable with the first mentioned group of tooth numbers, and the pair of gears on the jack shaft and the pair of gears on the intermittent mechanism driving shaft having respective numbers of teeth that are mutually commensurable within each pair and are incommensurable with both previously mentioned groups of tooth numbers.
